Lauretta S. Madda, Chicago, Ill.

Application August 9, 1951, Serial No. 16,218

Term of patent 7 years

(Cl. D54—12)

To all whom it may concern:

Be it known that I, Lauretta S. Madda, a citizen of the United States, residing at Chicago, county of Cook and State of Illinois, have invented a new, original, and ornamental Design for a Combined Relish Spoon and Fork, of which the following is a specification, reference being had to the accompanying drawing, forming part hereof.

Fig. 1 is a front elevational view of a combined relish spoon and fork, showing my new design;

Fig. 2 is a side elevational view of the same, and

Fig. 3 is a section on the line 3—3 of Fig. 2.

I claim:

The ornamental design for a combined relish spoon and fork, substantially as shown.

LAURETTA S. MADDA.
